DESIGN FOR A SPOON OR THE LIKE

Russell E. McKenna, Warwick, R. I., assignor to Walter H. McKenna & Co. Inc., a corporation of Rhode Island

Application September 24, 1948, Serial No. 148,753

Term of patent 3½ years

(Cl. D54—12)

To all whom it may concern:

Be it known that I, Russell E. McKenna, a citizen of the United States of America, residing at Warwick, county of Kent, State of Rhode Island, have invented a new, original, and ornamental Design for a Spoon or the like, of which the following is a specification, reference being had to the accompanying drawing, forming a part thereof.

Fig. 1 is a front view of a spoon or the like showing my new design; and

Fig. 2 is a side elevational view of the spoon or the like.

The dominant part of the design is shown in full lines.

I claim:

The ornamental design for a spoon or the like, substantially as shown and described.

RUSSELL E. MCKENNA.
